UNITED STATES PATENT OFFICE.

BROR J. LINDGREN, OF BUFFALO, NEW YORK, ASSIGNOR TO NIAGARA MACHINE & TOOL WORKS, OF BUFFALO, NEW YORK, A CORPORATION OF NEW YORK.

MACHINE FOR COMPRESSING CORRUGATED PIPES.

Application filed March 24, 1922. Serial No. 546,482.

To all whom it may concern:

Be it known that I, BROR J. LINDGREN, a citizen of the United States, residing in the city of Buffalo, in the county of Erie and ⁵ State of New York, have invented new and useful Improvements in Machines for Compressing Corrugated Pipes, of which the following is a specification.

This invention relates to a machine for ¹⁰ endwise compressing a pipe which has previously been formed of a sheet of metal rolled into a tube and provided with circumferential corrugations, this compressing operation being one of the steps for converting a sheet of metal into a stove pipe elbow or similar article.

The object of this invention is the production of a machine whereby pipes of this character may be compressed properly and ²⁰ expeditiously and with a minimum expenditure of labor and power and which permits of using the main parts of the machine for compressing pipes of various diameters.

In the accompanying drawings: ²⁵ Figure 1 is a top plan view, partly in section, of a compressing machine embodying my invention. Fig. 2 is a vertical longitudinal section of the same, showing the parts in position preparatory to compressing a ³⁰ pipe endwise. Fig. 3 is a similar view showing the position of the parts after the compression of a pipe has been completed. Fig. 4 is a fragmentary longitudinal section of the lower part of the chuck with a raised ³⁵ top part thereof in dotted lines and the upper section of the movable abutment or plunger swung into open or retracted position. Fig. 5 is a cross section taken on line 5—5, Fig. 1, and showing the chuck closed. Fig. ⁴⁰ 6 is a similar view but showing the chuck open. Fig. 7 is a fragmentary cross section on line 7—7, Fig. 1. Figs. 8 and 9 are fragmentary longitudinal sections of the mold or body of the chuck, the movable abutment ⁴⁵ or plunger and internal supporting member associated therewith showing the method of holding the pipe and compressing the same. Fig. 10 is a perspective view of one of the internal pipe supporting rings of the

chuck. Fig. 11 is a similar view showing ⁵⁰ a pipe after the same has been compressed by my improved machine.

Similar characters of reference refer to like parts throughout the several views.

The pipe 20 which is to be compressed endwise by the machine of my invention is constructed of a sheet of metal which is first provided with corrugations on its central part while its end portions are uncorrugated and then the same is rolled into the form of ⁶⁰ a tube so that the corrugations 21 extend circumferentially around the pipe and its opposite ends 22 are of plain cylindrical or uncorrugated form, as shown in Fig. 2. The pipe in this form has its corrugations spread ⁶⁵ apart, as shown in Figs. 2 and 8 and the same is then subjected to the endwise compressing operation of the present machine whereby its corrugations are pressed or folded closely to each other, as shown in ⁷⁰ Figs. 3, 9 and 11, preparatory to bending the pipe into elbow shape.

My improved machine for compressing the pipe endwise is constructed as follows:

23 represents the main frame of the machine which may be of any suitable construction to support the several working parts. On one end of this frame is mounted the chuck which receives the pipe to be compressed. In its preferred form this ⁷⁵ chuck is so constructed that some parts of the machine may be used for endwise compressing pipes of different length and diameter and thus avoid the expense which otherwise would be involved and a corresponding increase in space required if a complete machine were needed for each size of pipe. For this purpose a main mold or chuck body is permanently mounted on the main frame and adapted to form part of the ⁸⁰ chuck for compressing pipes of the largest diameter and the greatest length and supplemental mold or chuck bodies adapted to form parts of chucks for compressing pipes of smaller diameter and less length are provided which may be mounted in the main ⁸⁵ chuck body and thus permit of using the main parts of the same machine for com-

pressing various sizes of pipes. As shown in the drawings the main chuck body is constructed in the form of a horizontal cylinder which is divided lengthwise to provide a lower semi-cylindrical section 24 which is normally fixed on the main frame and an upper semi-cylindrical section 25 which is connected with the lower section so as to be movable laterally toward and from the lower section. The lower body section is preferably so mounted on the main frame that it can be adjusted lengthwise to suit other parts of the machine with which it cooperates and for this purpose the lower body section 24 is provided on its opposite sides with laterally projecting lugs 26 which rest on the upper horizontal face 27 of the frame and receive fastening bolts 28 which pass through longitudinal slots 29 in the upper part of the frame, as shown in Figs. 1, 5 and 6. Longitudinal adjustment of the mold or body of the main chuck is effected by a horizontal adjusting screw 30 journaled in a bearing 31 on the main frame but held against longitudinal movement therein and engaging its inner end with a threaded opening 32 formed in a lug 33 depending from the underside of the mold section 24, while its outer end is provided with a handle 34 for turning this screw, as shown in Fig. 2. The upper section 25 of the body or mold of the main chuck is preferably pivotally connected at one of its longitudinal edges with the corresponding edge of the companion lower section 24 by hinges 35 so that this upper section can swing vertically toward and from the lower section for opening and closing the mold of the chuck. The upper mold section may be locked in its closed position by a fastening device which in its preferred form comprises two locking lugs 36 arranged on the lower mold section 24 adjacent to the ends of that longitudinal edge thereof opposite to the hinges 35 and forming downwardly facing shoulders, two upright bifurcated catches 37 each having a hook 38 at its lower end adapted to engage the underside of one of said locking lugs, two vertically swinging elbow levers pivoted on the free longitudinal edge of the upper mold section 25 and each having an upright upper arm 39 upon which the upper end of one of the catches is pivoted and a lower horizontal arm 40 which projects outwardly and which is connected by a handle 41 with the corresponding arm of the other elbow lever so that both catches may be opened and closed in unison. In operation the catches engage automatically with the locking lugs when lowering the upper mold section 24 upon the lower mold section 25 and upon raising the handle 41 the upper arms of the elbow levers swing inwardly together with the upper ends of the catches whereby

the intermediate parts of the latter are caused to turn on the adjacent surface of the upper mold section 25 as a fulcrum and move outwardly at their lower ends so that the hooks therefore disengage from the locking lugs.

In the present instance the mold or body of the main chuck is not used for compressing a pipe endwise but serves as an outer support for the mold or body of an inner or supplemental chuck of smaller size designed to compress a pipe which is shorter and of smaller diameter. This inner or supplemental chuck body or mold has the form of a horizontal cylinder which is divided lengthwise into lower and upper semi-cylindrical sections 42, 43 which fit against the inner side or bore of the corresponding sections of the outer or main body sections and are detachably connected therewith by screws 44, as shown in Figs. 1, 2, 3 and 4, or otherwise. Adjacent to the front ends of the outer mold sections 24, 25 the same are provided with inwardly facing annular shoulders 50 which are engaged by the adjacent outer ends of the inner mold sections 42, 43, as shown in Figs. 2, 3 and 4, and adjacent to their outer ends the inner mold sections are provided in the bore thereof with inwardly facing annular shoulders 45. Against the latter is fitted a longitudinally immovable abutment ring which engages with the adjacent enlarged part of the bore of the inner mold or body and is split axially so that the same is divided into lower and upper sections 47, 48 which are detachably secured by screws 49 to the lower and upper sections 42, 43 of the inner mold and are provided with an inwardly facing shoulder 46.

Within the rear end of the inner mold is arranged a movable abutment head or plunger which is recessed on its inner side so as to form an inwardly facing shoulder or abutment 52. This plunger is of cylindrical form to fit the bore of the inner mold and the same is divided to form a lower section 53 which is only capable of a longitudinal movement and an upper section 54 which is pivotally connected by a pin 55 to the lower section so that the same is capable not only of moving lengthwise with the lower section 53 but also swinging vertically relatively thereto to permit of introducing the pipe to be compressed to this plunger as well as removing the same therefrom.

During the operation of endwise compressing a pipe the uncorrugated end portions thereof are preferably supported against being displaced inwardly under the endwise pressure against the same by placing within each of the ends of the pipe a supporting ring 56 so that the same are flush with the ends of the pipe. The rings are placed in the pipe before the latter is

put in the machine and thereafter the un-compressed pipe is placed with its lower half into the lower section of the supplemental mold or body of the chuck so that 5 its corrugated central part is arranged between the abutment ring and the abutment plunger and the lower half of one of its uncorrugated ends engages the lower half of the recess in the plunger and the lower 10 half of its opposite uncorrugated end engages the inner enlarged part of the bore of the abutment ring.

The upper section of the abutment plunger is now swung downwardly so that its portion 15 of the plunger recess also engages the upper portion of the respective end of the pipe and this end of the pipe is confined within the recess of the plunger. The upper half of the outer and inner molds are now lowered so that the central part of the upper 20 section of the supplemental mold encloses the upper half of the corrugated part of the pipe and one end of this mold embraces the upper half of the plunger and the upper half 25 of the abutment ring engages the upper half of the other end of the pipe, as shown in Figs. 2 and 8. The plunger is now moved forwardly while the ends of the pipe are securely held against inward displacement, whereby the circumferential corrugations on 30 the central part are pressed together from the spread condition of the same, shown in Figs. 2 and 8, to the closely folded condition, shown in Figs. 3 and 9, which is attended by a corresponding shortening of the pipe. The plunger is next moved to its retracted 35 position, and the upper half of the mold is raised to permit of removing the compressed pipe, from the lower half of the mold and the ring and plunger abutments. After the 40 pipe is removed from the machine the internal supporting rings are detached therefrom and inserted in another uncomressed pipe preparatory to compressing the same in the manner described.

During the operation of raising and lowering the upper section of the mold its weight is preferably counterbalanced by a counter-weight which may consist of two arms 50 projecting laterally from the hinged side of the upper mold section and each having one or more weights 58 adjustably secured thereto by a screw 59. The opening movement of the upper half of the mold is preferably arrested when this half has made substantially a quarter turn, this being preferably accomplished by a stop 60 having the form of an upright bar secured at its lower end to the main frame while its upper 55 end is arranged in a position to be engaged by the outer side of the upper mold section, as shown in Fig. 6.

When a pipe of largest diameter and greatest length within the capacity of the 60 machine is to be compressed endwise the

upper and lower sections 42, 43 of the supplemental or smaller mold are detached from the upper and lower sections 25, 24 of the main or largest mold and removed together with the abutment plunger and the 70 sections of the abutment ring employed for compressing pipes of smaller diameter and shorter length, and in their stead upper and lower abutment ring sections of corresponding larger diameter are substituted for the 75 sections 47, 48 and secured to the bore of the large or main sections and against the shoulders 45 thereof, and a plunger corresponding to that used in the smaller mold but of a larger size is substituted therefor 80 and placed within the opposite end of the larger or main mold. When thus fitted with a larger abutment ring and a larger abutment plunger the main mold sections 85 form the main elements for enclosing and compressing a large pipe endwise, it being understood that internal supporting rings 56 of correspondingly increased diameter are employed when operating on pipes of the larger size.

Any suitable means may be employed for reciprocating the longitudinally movable plunger or abutment in the mold which means are however preferably constructed as shown in Figs. 1, 2 and 3. As there 90 shown the same comprise a driving shaft 61 journaled transversely in bearings on the upper part of the main frame and provided with a crank 62, a connecting rod 63 pivotally connected at one end with said crank, a 100 longitudinally reciprocating slide or carriage 64 guided in ways 80 on the main frame and pivotally connected on its rear side with the opposite end of said connecting rod, and a longitudinal shifting rod 65 105 which is connected at its rear end with said slide and at its front end with said plunger 53, 54. The rear end of the shifting rod is preferably detachably connected with the slide by providing this rod near its rear end 110 with a reduced neck 66 forming a head 67 at the end of the rod, and providing the front side of the slide with a correspondingly shaped socket which is formed between a saddle 69 on the lower part of the slide and a detachable cap 70 secured to this saddle by screws 71, as shown in Figs. 2 and 7, or otherwise. The connection between the front end of the shifting rod and the plunger is preferably effected by providing this 115 end of the rod with a reduced neck 68 which is arranged in an opening 51 formed horizontally and centrally in the head of the lower section 53 of the compressor plunger, a forwardly facing shoulder 73 engaging with the outer side of this head, and a collar 74 of larger diameter than the neck 68 secured to the front end thereof by a screw 75 and bearing against the front side of the plunger head. When a pipe of the great- 120 125 130

est length is being compressed in the machine the neck 68 of the shifting rod is so fitted in the plunger that the same are incapable of moving independently of each other but are compelled to move in unison, thereby imparting the maximum throw of the crank to the plunger and moving the latter lengthwise the requisite extent for operating on the pipes of greatest length for which the machine is intended. When, however, shorter pipes are to be compressed in the machine a connection between the shifting rod and the plunger is so fitted that a lost motion or slack connection is obtained between the same lengthwise of the path of these parts. This is preferably obtained by making the neck 68 of the shifting rod longer than the head of the respective plunger, as shown in Figs. 1, 2, 3 and 4 which produces a certain amount of dead movement in the shifting rod and only transmit part of its movement to the plunger. The amount of this dead, slack or lost motion varies according to the length of the pipe which is being compressed and for this purpose a shifting rod and plunger having the requisite amount of longitudinal play between the same are provided for each mold in which a definite length of pipe is to be compressed.

In actual practice the diameter of the pipes usually increase in the same measure as the increase in length and a machine of this character therefore equipped with a plurality of sets of molds, abutment rings, plunger and shifting rods, any one set of which may be operated in the machine for compressing pipes of a predetermined length and diameter.

As shown in the drawings the driving shaft may be operated by a counter shaft 76 journaled transversely in the lower part of the frame and provided at one end with a belt pulley 77 and connected at its other end by gear wheels 78, 79 with the driving shaft. This machine is preferably controlled so that the same after being started performs a cycle of operations, the same is automatically stopped, each cycle including a forward and backward stroke of the plunger. For this purpose the driving shaft is provided with an automatic clutch 81 which is controlled by a treadle 82 operatively connected therewith in any suitable manner.

This machine aside from being very strong and durable in construction, permits of compressing pipes rapidly and without liability of producing defective work, thereby insuring a large capacity and economy in production.

I claim as my invention:

1. A machine of the character described comprising a chuck having a cylinder which is adapted to receive a circumferentially

corrugated pipe, abutments adapted to engage opposite ends of the pipe and one movable relatively to the other lengthwise of the cylinder, means for reciprocating said movable abutment, and means for adjusting the position of said cylinder in a direction lengthwise of its axis. 70

2. A machine of the character described comprising a chuck having a cylindrical body which is adapted to receive a circumferentially corrugated pipe, a relatively stationary abutment arranged in said body and adapted to be engaged by one end of the pipe and a movable abutment adapted to engage with the exterior of the other end of said pipe and having a section which is movable longitudinally, and a section which is movable lengthwise with said first mentioned section and also capable of moving laterally relatively thereto. 90 95

3. A machine of the character described comprising a chuck having a cylindrical body which is adapted to receive a circumferentially corrugated pipe, a relatively stationary abutment arranged in said body and adapted to be engaged by one end of the pipe, and a movable abutment adapted to engage with the other end of said pipe and having a section which is movable longitudinally, and a section which is pivoted to the first mentioned section so as to be capable of swinging transversely relatively thereto. 95

4. A machine of the character described comprising a chuck having a cylindrical body which is adapted to receive a circumferentially corrugated pipe and which is divided lengthwise into sections one of which is normally fixed and the other movable laterally relative to the fixed section, said body being provided with a relatively stationary abutment which is adapted to engage one end of said pipe and which is divided lengthwise into sections one of which is arranged on the normally fixed section of said body and the other arranged on the transversely movable section of the body, and a normally movable abutment adapted to engage the other end of said pipe and consisting of sections one of which is movable lengthwise only in the body and the other being pivoted to said longitudinally movable section so as to move lengthwise therewith and also capable of swinging transversely thereto. 110 115

5. A machine of the character described comprising a chuck having a cylindrical body which is adapted to receive a circumferentially corrugated pipe and which is divided lengthwise into sections one of which is normally fixed and the other movable laterally relative to the fixed section, said body being provided with a relatively stationary abutment which is adapted to engage one end of said pipe and which is divided lengthwise into sections one of which is arranged on the normally fixed section of said 120 125 130

- body and the other arranged on the transversely movable section of the body, a normally movable abutment adapted to engage the other end of said pipe and 5 consisting of sections one of which is movable lengthwise only in the body and the other being pivoted to said longitudinally movable section so as to move lengthwise therewith and also capable of swinging 10 transversely thereto, and supporting rings adapted to be placed within the end portions of said pipe.
6. A machine of the character described comprising a chuck having a cylindrical body which is adapted to receive a circumferentially corrugated pipe and which is divided lengthwise into sections one of which is normally fixed and the other movable laterally relative to the fixed section, said body 15 being provided with a relatively stationary abutment which is adapted to engage one end of said pipe and which is divided lengthwise into sections, one of which is arranged on the normally fixed section of said body 20 and the other arranged on the transversely movable section of the body, and a normally movable abutment adapted to engage the other end of said pipe and consisting of sections one of which is movable lengthwise 25 only in the body and the other being pivoted to said longitudinally movable section so as to move lengthwise therewith and also capable of swinging transversely thereto, said relatively fixed abutment being constructed 30 in the form of a split ring and said body being provided with an internal shoulder 35 which is engaged by said split ring.
7. A machine of the character described comprising a chuck having a cylindrical body which is adapted to receive a circumferentially corrugated pipe and which is divided lengthwise into sections one of which is relatively stationary and the other pivotally connected at one of its longitudinal 40 edges to the corresponding longitudinal edge of the relatively stationary section so as to be capable of swinging transversely thereto, coupling means for detachably connecting the opposite longitudinal edges of the sections of said body, abutments which are arranged within the body and adapted to engage with opposite ends of the pipe, one of said abutments being relatively stationary and the other movable lengthwise 45 of the body, a main frame, lugs arranged on said body and provided with longitudinal slots, bolts passing through said slots and said frame, a lug arranged on the body and having a threaded opening, and an adjusting screw engaging said threaded opening, and mounted on said frame so as to be capable of turning but held against lengthwise movement.
8. A machine of the character described comprising a chuck having a cylindrical body which is adapted to receive a circumferentially corrugated pipe and which is divided lengthwise into sections one of which is relatively stationary and the other movable lengthwise of the body, and abutments which are arranged within the body and adapted to engage with opposite ends of the pipe, one of said abutments being relatively stationary and the other movable lengthwise of the body, said coupling means comprising a shoulder arranged on the relatively stationary body section, a latch having a hook adapted to engage said shoulder, and an elbow lever pivoted on the swinging body section and having one of its arms pivotally connected with said latch while the other arm thereof is provided with a handle.
9. A machine of the character described comprising a chuck having a cylindrical body which is adapted to receive a circumferentially corrugated pipe and which is divided lengthwise into sections one of which is relatively stationary and the other movable lengthwise of the body, and abutments which are arranged within the body and adapted to engage with opposite ends of the pipe, one of said abutments being relatively stationary and the other movable lengthwise of the body, a main frame, lugs arranged on said body and provided with longitudinal slots, bolts passing through said slots and said frame, a lug arranged on the body and having a threaded opening, and an adjusting screw engaging said threaded opening, and mounted on said frame so as to be capable of turning but held against lengthwise movement.
10. A machine of the character described comprising a chuck having inner and outer cylindrical bodies the outer one of which is adapted to be used alone when operating on pipes of the largest diameter and the inner body being supported within the outer body and adapted to receive pipes of a smaller diameter, each of said bodies being provided internally with an abutment immovable lengthwise for engaging one end of the pipe to be operated upon and a longitudinally movable abutment for engaging the opposite end of the respective pipe.
11. A machine of the character described comprising a chuck having a cylindrical body adapted to receive a circumferentially corrugated pipe, a longitudinally immovable abutment arranged within the body and adapted to engage with one end of the pipe, a longitudinally movable abutment arranged within the body and adapted to engage with the other end of the pipe.

engage with the other end of the pipe, a main frame on which the body is mounted, a driving shaft journaled on the frame and having a crank, a connecting rod connected at one end with said crank, a slide movable lengthwise on the frame and connected with the other end of said rod and having a

divided socket, a shifting rod provided at one end with a reduced neck which is seated in said socket while its opposite end is reduced and slides in said longitudinal movable abutment and is provided with shoulders on opposite sides of this abutment. ¹⁰

BROR J. LINDGREN.
